UNITED STATES PATENT OFFICE.

WILLIAM J. LONGMORE, OF BELLEVUE, PENNSYLVANIA, ASSIGNOR TO WESTINGHOUSE ELECTRIC AND MANUFACTURING COMPANY, A CORPORATION OF PENNSYLVANIA.

PROCESS OF MANUFACTURING INSULATING MATERIAL.

1,138,676.

Specification of Letters Patent. Patented May 11, 1915.

Application filed February 16, 1912. Serial No. 678,125.

To all whom it may concern:

Be it known that I, WILLIAM J. LONGMORE, a citizen of the United States, and a resident of Bellevue, in the county of Allegheny and State of Pennsylvania, have invented a new and useful Improvement in Processes of Manufacturing Insulating Material, of which the following is a specification.

10 My invention relates to processes of manufacturing insulating material from flakes or scales of mica, and it has for its object to provide a process whereby built-up sheets or plates of mica of uniform thickness may 15 be produced expeditiously and economically and with the exercise of but little care in the handling.

Plates or sheets of insulating material have heretofore been manufactured by causing mica scales and powdered-binding material to fall in a shower, within a comparatively high tower, upon a plate or support at the lower end of the tower, the mica scales and the binder being thus distributed 25 upon the receiving support with remarkable uniformity. When sufficient mica has, in this manner, been deposited upon the receiving plate to provide a finished sheet of the desired thickness, the assembled mica 30 and binder are removed from the lower end of the tower and preliminarily heated and pressed to melt the binder and to cause the mica flakes to adhere together, and then finally heated for a considerable period 35 while under great pressure in order to press and drive out the excess of the binder and to thoroughly compact the sheet. Owing to the fact that the flakes of mica and the comminuted binder are deposited in a loose condition upon the receiving plate, it is difficult 40 to remove the assembled materials from the tower without displacing the same and thereby rendering the plate of non-uniform thickness, or otherwise injuring it.

45 According to the present invention, the flakes of mica and the comminuted binder are deposited as above indicated upon a heated plate or support, the heat from which serves to melt the binder and to effect 50 a preliminary cementing together of the mica flakes while the assembled materials are still in the tower, so that there is little liability of displacing the flakes or other-

wise injuring the sheet during the removal thereof from the tower.

55 Figure 1 of the accompanying drawing, is a view, in side elevation and in section, of a part of a suitable tower in connection with which the first step of the present invention is practised, and Fig. 2 is a view, in side elevation, of apparatus for practising the final step of the present process.

60 In practising the present invention, loose mica flakes or scales and a comminuted binder, such as dry powdered shellac, are distributed, preferably separately and alternately, in the upper end of a suitable tower 1, and are permitted to fall in a shower from the top to the bottom thereof upon a suitable heated receiving plate or support 2 at the 65 bottom of the tower, the mica flakes being thus entirely disassociated and detached from each other, and being also uniformly distributed upon the receiving plate.

70 The receiving plates may be heated outside the tower and placed therein while hot, or, if desired, they may be heated while in the tower by any suitable means, as by providing them with electric heating elements which are preferably embedded or inclosed 75 therein, substantially as indicated in Fig. 2. The plates are placed in the tower through a door 3 in its side and are preferably placed 80 therein in succession as the desired quantities of mica and shellac are deposited thereon, the new plate being laid, in each case, upon the loose mica and binder that has 85 been previously deposited upon the lower plate. The upper plates thus serve as weights to compress the mica scales, while 90 the heat melts the comminuted binder and causes the mica flakes to be preliminarily cemented with sufficient security to insure 95 against their displacement during the removal thereof and of the receiving plate 95 from the tower. When the receiving plates have cooled, the preliminarily cemented 100 mica sheets are of sufficient strength to permit of their being removed from between the receiving plates and of being 100 handled as desired. In order that the 105 assembled sheets of mica flakes may not adhere to the receiving plate 2, a sheet of paper is preferably placed upon the receiving plate before the mica and binder are applied thereto. The preliminarily cemented mica

sheets are next and finally placed in a press and again heated for a considerable period while under heavy pressure for the purpose of driving out the excess of binder and of thoroughly compacting the sheets, suitable means for effecting this result being shown in Fig. 2.

While it will generally be found preferable to provide a heated plate for receiving the first deposit of commingled mica flakes and comminuted binding material, the deposit may be made upon a cold plate, if desired, since the heat imparted by the second plate and the combined weight of that and the other superposed plates and layers of mica and binding material will serve to effect such union of the materials as will permit of the handling which is incident to the subsequent steps of the complete process.

20 I claim as my invention:

1. The process of manufacturing an insulating sheet which consists in distributing a shower of commingled scales of mica and a comminuted dry bond upon a heated member and then applying heat and pressure to the upper surface of said material while the said material and member are in their original position.

2. The process of manufacturing an insu-

lating sheet which consists in distributing a shower of commingled scales of mica and a comminuted dry bond upon a plane surface within a chamber and subsequently applying heat and pressure to the upper surface of said distributed material without removing it from the chamber.

3. The process of manufacturing insulating sheets which consists in distributing showers of commingled scales of mica and a comminuted dry bond upon each of a plurality of successively superposed heated members.

4. The process of making insulating sheets which consists in depositing a shower of commingled mica flakes and comminuted dry binding material upon a plane surface, placing a heated plate upon said deposited materials, depositing another shower of said materials upon said heated plate, and applying thereto another heated plate.

In testimony whereof, I have hereunto subscribed my name this 5th day of Feb. 1912.

WILLIAM J. LONGMORE.
